SEY, A CORPORATION OF DELAWARE.

ART OF HEAT CONVERSION OF HYDROCARBON OILS.

Application filed November 28, 1921. Serial No. 518,199.

The present invention relates to the heat conversion of hydrocarbon oils more particularly for the production of low boiling-point hydrocarbon oils such as gasoline, and 5 will be fully understood from the following description illustrated by the accompanying drawings, in which Fig. 1—shows apparatus suitable for carrying out the invention, somewhat diagrammatically and partly in 10 section, Fig. 2—shows a modified form of apparatus suitable for carrying out the invention, somewhat diagrammatically and partly in section.

The stock handled in practicing the present invention may suitably be any hydrocarbon oil of higher boiling-point than the desired products of conversion. In the present process stocks of widely varying types may be employed, crude or residue stocks being available as well as "overhead" or distillate stocks, such as the frequently employed gas-oils. Thus the feed stock for the present process may suitably be a reduced light Mexican crude, a reduced California 25 crude, a heavy Mexican crude or other crude or residue oil, notwithstanding the formation of extremely large amounts of carbon during the heat conversion. Thus the present process has been successfully carried out, 30 not only on gas-oils and similar oils, but also on such oils as heavy Mexican crude petroleum having a gravity of 11.5 to 12.5 Baumé and a viscosity of 800 to 900 Saybolt at 210° F.

Referring to Figure 1, the stock, which may previously have been preheated, if desired, is fed by pump 1 through pipe 2 into a fired coil 3 mounted in a suitable furnace setting 4. This coil may be constructed, for example, of four inch pipe and may have an aggregate length, for example, of about 1,600 feet, although both dimensions may be widely varied. The coil is fired vigorously, so that the oil passing out of it has 45 a temperature within the range of 750 to 900° F., say 800 to 850° F. The stock is fed through the coil at a rate such that there is substantially no coke deposition in the coil, a suitable rate being 2,000 gallons per hour 50 with a coil of the dimensions above described. For a given outlet temperature of the oil, the velocity of the oil in the coil

may be modified in any suitable manner, for example, by increasing the firing rate and the feed rate simultaneously or by supplying steam or gas, or water or a readily volatile hydrocarbon oil, such as gasoline, which vaporizes at once, into the coil through the pipe 5. The added vapor constituent mixes with the oil in the coil in 60 the form of bubbles, and increases its volume and consequently its velocity without absorbing a proportionate amount of heat in passing through the coil.

The oil passes through the coil very rapidly, acquiring an efficient cracking temperature, its passage through the coil being so fast that only incipient cracking takes place within the coil, with relatively little or no coke formation and deposition. The oil 70 leaving the coil does not contain a high proportion of low boiling conversion products; the change in the oil being indicated mainly by a drop in viscosity and a small increase in Baumé gravity.

After passing from the coil 3 the oil passes into the first drum 6 of a series or succession of drums or enlarged chambers. In the form of apparatus shown in the drawing, two such drums or enlarged chambers are shown in series. These drums are of such size relative to the coil that the oil remains therein for a considerable period, say 1½ to 2 hours. The first of the drums, designated by numeral 6, is lagged with a 85 thick coating of heat insulating material so as to prevent any substantial loss of the contained heat of the oil entering the drum. The oil, in passing through the drum 6, may drop in temperature 50 to 75°, so that the 90 outlet temperature of the oil from drum 6 is from 700 to 850°. Thus where the outlet temperature of the oil from the coil is 800 to 825°, the outlet temperature of the oil from the drum 6 is from 740 to 770° F. A 95 considerable deposition of coke takes place in the drum 6 and is readily removable therefrom.

The oil passes out of the drum 6 through a pipe 7, the inlet of which may be at the 100 top of the drum or may be considerably below the top of the drum 6 as here shown. In the former case, the drum remains completely full of liquid, while in the latter the

liquid level is maintained at the level of the outlet pipe, that is the top of the drum serves as a vapour space. The former arrangement is preferred except in the conversion of very light oils such as kerosene, in which cases the latter arrangement has advantages.

The oil passing out of drum 6 to pipe 7 enters drum 8, which is an enlarged container in which the oil remains for a period approximately the same as its period of stay in drum 6. The drum 8 is mounted in a suitable setting so that it may be mildly heated, for example, by the waste combustion gases from the setting 4 of the coil 3, which enter the setting 9 of drum 8 through flue 10. The heat applied to the drum 8 is at no time sufficient to raise the surface temperature of the drum above 900° F., and does not raise the temperature of the oil in the drum above its temperature at the outlet of drum 6. In the drum 8 the temperature of the oil may be permitted to drop so that at the outlet of the drum it has a temperature of not less than about 700° F. Thus, when the temperature at the outlet of drum 6 is 740 to 770° F., the temperature at the outlet of drum 8 may suitably be 690° F. to 725° F. In each of the drums 6 and 8 there is a marked amount of conversion of the oil into the desired low boiling products. In the drum 8 there is a considerable deposition of coke, which, by reason of the mild heating of the drum, is not baked to the surface of the latter and may be readily removed.

The products of conversion are drawn off together from the drum 8 through the outlet pipe 11, to be cooled, for example, by heat exchange with fresh feed stock, and to be separated into their various fractions. Pressure is maintained upon the entire system at least sufficient to maintain the original stock in the liquid phase at the temperature of the drums until modified by considerable pyrolysis. The pressure may, for the stock particularly described, be 150 to 180 pounds or higher. It is preferred that much higher pressure, for example, 250 to 350 pounds be employed, particularly for converting lighter oils, such as kerosene.

In the form of apparatus shown in Figure 2, a coil 12 of similar construction to coil 3 Figure 1 is mounted in a suitable setting, in which it is highly heated so that the oil forced through it under conditions similar to those described in connection with the previous form of apparatus is brought to a temperature within the range of 750 to 900° F., say 800 to 825° F. at the outlet from the coil. Steam or other suitable gas or vapour, or vapourized liquid may be introduced into the coil through the pipe 13.

From the coil the heated oil passes into an enlarged chamber or drum 14, covered with a thick covering of heat insulating ma-

terial, this drum being similar in character to drum 6 previously described. Here the oil is retained while a substantial conversion into low boiling-products takes place under the conditions described with the previous construction of apparatus. The heat of the oil is retained by the heavy lagging on the drum and the oil leaves the drum only slightly lowered in temperature. Thus the oil at the outlet of drum 14 may have a temperature within the range of 700 to 850° F.; for example, when the oil entering the drum has a temperature of 800 to 825° F., on leaving the drum it will have a temperature of 740 to 770° F. After leaving the drum 14, the oil passes into a second heavily lagged drum 15, the construction of which is substantially similar to that of the drum 14. The oil is retained in this drum a further period during which a substantial conversion into the desired low boiling-point product takes place, the period being substantially the same as that during which the oil remains in the drum 14. In order that the oil may not fall below an efficient cracking temperature of say 680 to 700° F. in the drum 15, means are provided for supplying heat internally within the drum. This heat is suitably supplied by introducing into the drum in suitably regulated quantities a form of oxygen containing gas, such as air. At the temperatures prevailing within the drum, the supply of oxygen causes immediate and spontaneous combustion of corresponding quantities of the hydrocarbon material within the drum, the heat thus liberated maintaining the oil at the proper temperature.

In the form of apparatus illustrated, the air or other oxygen containing gas is forced by pump 16 through a suitable heating device 17, in which it is brought to a temperature of preferably 700 to 900° F. From the heating device 17, the heated air passes through valved pipe 18 into a distributing head 19 within the drum. The preheating of the air makes the heat supplied by combustion within the drum substantially entirely available for heating and maintaining the temperature of the oil.

The supply of air or oxygen containing gas is regulated by the valved pipe 18 to supply sufficient heat within the drum so that the temperature of the products of conversion leaving the drum through outlet pipe 20 will be not less than 700 to 750° F. The supply of air should in general, however, not be so great as to bring the temperature of the oil leaving the drum 15 above that of the oil leaving the coil 12. It is usually sufficient that oil leaving the drum shall be above 680 to 700° F. and not more than 50 to 75° below the temperature of the oil leaving the drum 14. For example, when the oil leaving the drum 14 has a temperature

of 740 to 770° F., the temperature of the products leaving the drum 15 may be from 725 to 750° F.

In the case of the 12° Baumé oil referred 6 to the process as described in connection with either form of apparatus effects such conversion of the oil that when distilled it will produce about 20 to 25% or upwards of distillate having a gravity of gasoline 10 or kerosene, say for example, 48° Baumé, and the rate of feed and withdrawal of oil may be adjusted to produce approximately this conversion.

We claim:

15 1. In apparatus for the conversion of oil, the combination of a coil, means for forcing oil therethrough, means for applying highly heated combustion gases to the coil, an enlarged unheated chamber into which the coil 20 discharges, said chamber being provided with means for hindering the escape of heat and having a single outlet, a second enlarged chamber into which the first mentioned chamber discharges, and means for supplying the waste combustion gases to heat the second chamber after having been applied to the coil.

2. In apparatus for the conversion of oil, a combination of a coil, means for forcing oil therethrough, means for heating the coil 30 to secure cracking temperature therein, an enlarged chamber into which the coil discharges, said chamber being provided with means for hindering the escape of heat from the chamber, thereby maintaining a cracking 35 temperature therein, a second enlarged chamber into which the first mentioned chamber discharges, and means for supplying heat internally within the second chamber to maintain a cracking temperature 40 therein.

3. In apparatus for the conversion of oil, a combination of a coil, means for forcing oil therethrough, means for highly heating 45 the coil to secure cracking temperature therein, an enlarged chamber into which the coil discharges, means for retaining the heat of the oil within said chamber to maintain a cracking temperature therein, a second 50 enlarged chamber into which the heated oil from the first mentioned chamber is discharged, and means for supplying free oxygen containing gas into the second chamber, thereby maintaining a cracking temperature 55 therein.

4. In apparatus for the conversion of oil, a combination of a coil, means for forcing oil therethrough, means for highly heating the coil to secure a cracking temperature 60 therein, an enlarged chamber into which the coil discharges, said chamber having a single outlet, means for retaining the heat of the oil within said chamber, to maintain a cracking temperature therein, a second enlarged chamber into which the heated oil 65

from the first mentioned chamber is discharged through said outlet, means for heating free oxygen containing gas, and means for supplying the heated oxygen containing gas within the second chamber to maintain 70 a cracking temperature therein.

5. In apparatus for heating oil, an externally unheated chamber, means for continually supplying heated oil within said chamber, and for maintaining a liquid body of such oil therein, such chamber having a single outlet, means for supplying an oxygen containing gas within the chamber whereby combustion of corresponding proportions of the oil product contained therein is caused 80 to maintain the temperature of the oil body, and means for continually withdrawing the heated conversion products from said chamber through said single outlet.

6. The process of converting hydrocarbon 85 oils into hydrocarbon oils of lower boiling-point which comprises forcing the oil to be converted through a highly heated confined passage-way with a velocity sufficient to prevent substantial deposition of coke, the oil being thereby brought to conversion temperature, discharging the oil into an enlarged chamber while confining therein the contained heat of the oil, to maintain the oil at conversion temperature and passing the combined products of conversion together from 90 said enlarged chamber into a second enlarged chamber, the walls of which are heated to maintain conversion temperature 95 of the oil, the wall temperature thereof being not above 900° F.

7. The process of converting hydrocarbon 100 oils into hydrocarbon oils of lower boiling-point which comprises forcing the oil to be converted through a highly heated confined 105 passage-way with sufficient velocity to prevent substantial deposition of coke the oil being thereby brought to conversion temperature, discharging the oil into and through a succession of enlarged chambers, 110 the contained heat of the oil being confined in the earlier of said chambers to maintain the oil therein at conversion temperature and the later of said chambers being heated only sufficiently to maintain the oil at conversion temperature.

8. The process of converting hydrocarbon 115 oils into hydrocarbon oils of lower boiling-point which comprises forcing the oil through a confined passage, heating the passage so that the oil discharged therefrom has a temperature of 750 to 900° F., the velocity of the oil in the confined passage being such that no substantial amount of coke is deposited therein, discharging the oil into an 120 enlarged chamber while confining therein the contained heat of the oil to maintain it at a conversion temperature and passing the products from said enlarged chamber, into 125 a second enlarged chamber supplying heat 130

to said second chamber sufficient to maintain the oil at conversion temperature and not more than sufficient to maintain the temperature of the oil at its entrance temperature.

9. The process of converting hydrocarbon oils into hydrocarbon oils of lower boiling-point which comprises forcing the oil through a confined passage, applying heat to bring the oil to a temperature of 800 to 825° F. when discharged from the passage, the oil being forced therethrough with sufficient velocity to prevent substantial deposition of coke, discharging the oil into an enlarged chamber while confining therein the contained heat of the oil to maintain it at conversion temperature, discharging the oil from said chamber at a temperature of 740 to 770° F. into a second enlarged chamber, and heating said second chamber so that the oil discharged therefrom has a temperature of 675 to 725° F.

10. The process of converting hydrocarbon oils into hydrocarbon oils of lower boiling-point which comprises forcing the oil through a confined passage, heating the passage so that the oil discharged therefrom has a temperature of 750 to 900° F., the velocity of the oil in the confined passage being such that no substantial amount of coke is deposited there, discharging the oil into an enlarged chamber while confining therein the contained heat of the oil, and passing the product from said enlarged chamber into a second enlarged chamber, introducing an oxygen containing gas into the second enlarged chamber whereby spontaneous combustion of corresponding proportions of the products therein is caused and regulating the quantity of such gas supplied to maintain the temperature of the oil in the second enlarged chamber not below 680 to 700° F.

11. The process of converting hydrocarbon oils into hydrocarbon oils of lower boiling-point which comprises forcing the oil through a highly heated confined passage with a velocity sufficient to prevent a substantial deposition of coke whereby the oil is brought to a cracking temperature, discharging the oil into an enlarged chamber while confining therein the contained heat of the oil to maintain it at cracking temperature, passing the products from such enlarged chamber into a second enlarged chamber, the heat supplied to the oil being such that it enters the second enlarged chamber at a temperature not below 680 to 700° F., and supplying within the second chamber regulated quantities of free oxygen containing gas to substantially maintain said temperature.

12. The process of converting hydrocarbon oils into hydrocarbon oils of lower boiling-point which comprises forcing the oil through a highly heated confined passage

with a velocity sufficient to prevent a substantial deposition of coke, discharging the oil into an enlarged chamber while confining therein the contained heat of the oil, passing the products from such enlarged chamber into a second enlarged chamber, the heat supplied to the oil being such that it enters the second enlarged chamber at a temperature not below 680 to 700° F., and supplying within the second chamber regulated quantities of heated free oxygen containing gas.

13. The process of heat treating oils to effect conversion thereof, introducing heated oil products at a temperature of 700 to 850° F., into a chamber, supplying air within said chamber, maintaining a liquid body of said oil products therein, whereby combustion of corresponding proportions of said oil products is spontaneously effected and heat supplied within said chamber, and removing the conversion products from within said chamber, the air supplied being regulated to maintain the temperature of the products removed from said chamber not below 680 to 700° F.

14. The process of heat treating hydrocarbon oils to effect conversion thereof, supplying oil products at a temperature of 740 to 770° F. within a chamber, maintaining a body of the oil products therein, introducing air into said chamber whereby spontaneous combustion of corresponding proportions of the oil products therein is effected and heat is supplied therein, and withdrawing the conversion products from said chamber, the supply of air being regulated so that the temperature of the products withdrawn from said chamber is from 690 to 720° F. and maintaining pressure within said chamber sufficient to retain some of said products in liquid state.

15. The process of heat treating hydrocarbon oils to effect conversion thereof, supplying oil products at a temperature of 740 to 770° F. within a chamber, introducing heated air into such chamber whereby spontaneous combustion of corresponding proportions of the oil products therein is effected and heat is supplied therein, and withdrawing the conversion products from said chamber, the supply of heated air being regulated so that the temperature of the products withdrawn from said chamber is from 690 to 720° F.

16. The method of heat treating oils for effecting conversion thereof which comprises rapidly heating such oils, maintaining a liquid body of the heated oil at a temperature not below 680° F., and introducing free oxygen containing gas into the heated oil in proportion to cause sufficient combustion to maintain the temperature of the oil at not below 680° F.

17. The process of heat treating oils to

- effect conversion thereof, introducing heated oil products at a temperature of at least 700° F., into a chamber, supplying air within said chamber, maintaining a liquid 5 body of said oil products therein, whereby combustion of corresponding proportions of said oil products is spontaneously effected and heat supplied within said chamber, and removing the conversion products from 10 within said chamber, the air supplied being regulated to maintain the temperature of the products removed from said chamber not below 700° F.
18. The process of converting hydrocarbon oils into hydrocarbon oils of lower boiling point which comprises forcing the oil to be converted through a highly heated confined passageway to bring the oil to conversion temperature and with a velocity 15 sufficient to prevent substantial deposition of coke, maintaining the oil at conversion tem-
- perature to secure conversion thereof, discharging products of such conversion into a chamber while at conversion temperature and supplying within said chamber an 25 oxygen-containing gas to maintain the products therein at conversion temperature.
19. The process of converting hydrocarbon oils which comprises continuously passing the oil to be converted through a highly 30 heated confined passageway to bring the oil to conversion temperature, continuously passing the oil at conversion temperature into an enlarged chamber, supplying within said chamber an oxygen containing gas to 35 maintain conversion temperature therein, and continuously taking off products from said enlarged chamber through a single outlet therefrom.
